ANDREW J. NEAFIE, OF MOUNTAIN LAKE, AND CHARLES B. FRENCH, OF DOVER, NEW JERSEY, ASSIGNS TO LACKAWANNA STEEL COMPANY, OF LACKAWANNA, NEW YORK, A CORPORATION OF NEW YORK.

SPLICE-BAR FOR RAILROAD-RAILS.

1,226,360.

Specification of Letters Patent. Patented May 15, 1917.

Application filed October 31, 1916. Serial No. 128,666.

To all whom it may concern:

Be it known that we, ANDREW J. NEAFIE and CHARLES B. FRENCH, citizens of the United States, residing, respectively, at 5 Mountain Lake, New Jersey, and at Dover, New Jersey, have invented new and useful Improvements in Splice-Bars for Railroad-Rails, of which the following is a specification.

10 Our invention relates to improvements in splice-bars for the joints of railway rails, whereby the danger of fracture and injury to such splice-bars is greatly diminished, and their life prolonged.

15 These splice-bars, or angle-bars, as they are often called, are made of many shapes, sometimes with depending flanges, and are adapted to fit the "fishing angle" of the rail section, and to engage the rail head and the 20 rail flange. A typical form is here shown.

When in position in the track the angle-bar spans the joint, and its upper edge, or bearing surface, comes in contact with the edges or corners on the lower edges of the 25 ends of the two rail heads. The result of this contact, when the tracks are in service, is first to cut and wear the angle-bar, and, second, to hammer and upset the metal and reduce its ductility,—thus weakening the 30 angle-bar at the point of greatest stress.

It will be understood that, when the line is in service and the trains are passing, the angle-bar is subjected to alternating strains of compression and tension in both its upper 35 and lower surfaces. Therefore the aforesaid cutting, wearing, hammering, etc., at the center in the top of the bar tends to weaken it at the point of greatest stress, when the top of the bar is brought in tension. This often 40 results in fractures having their beginning at the top in the metal so damaged by contact with the rail ends. Such fractures often cause serious accidents.

Our invention has for its object to prevent such contact and thereby to prevent the said injuries, fractures and accidents, and consists in providing a depression in the upper bearing surface of the splice-bar at or about its middle, thus producing and maintaining a small but sufficient clearance between the edges of the rail ends and the bar, whereby upsetting, wearing, cutting, etc., of the latter at that point is avoided, and the

condition and surface of the metal in the depression is maintained the same as when 55 finished. This maintains the full strength of the splice-bar at the center, where it is subjected to the greatest strains, and therefore produces a better joint and prolongs its life.

Our invention is shown applied to various forms of splice-bars in the accompanying drawing in which the reference numerals of this description are applied to corresponding parts in the various views. Figure 1 is a 60 side elevation showing our improved splice-bar in position at the rail joint. Fig. 2 is a vertical cross section of Fig. 1 taken at the joint, and somewhat enlarged. Fig. 3 is a partial inside elevation of one of the splice-bars. Fig. 4 is an end elevation of the same. Fig. 5 is an end elevation of a form of splice-bar, commonly called a fish-plate, provided with our invention.

In the figures, 1 indicates the rails having 75 their ends arranged adjacent with the usual small space between. These rail ends are connected by the splice-bars 2 of any desirable shape, arranged in pairs, one on each side of the rails, and secured firmly in position by bolts 3—3 and nuts 4—4 of any suitable shape.

To carry out the purposes and obtain the advantages of our invention, clearance is provided between the under surfaces of the 85 rail heads 5 at their extreme ends and the upper surface of the splice bar 2 by forming the depression 6 centrally in said upper surface. By this means contact with the sharp corners on the rail heads is entirely 90 prevented and avoided during the life of the joint.

This depression may be formed by any suitable means, for instance during the process of rolling when the metal is hot, but 95 might be formed by cutting, abrading or otherwise when the metal is either hot or cold. We much prefer however to modify the shape by rolling, or bulldozing at the desired point, while the metal is hot. For 100 thus the metal is merely displaced without any reduction, at the point in question, and the bar is not weakened but is maintained of uniform strength from end to end.

We do not desire to limit ourselves to any 105 particular dimensions for this depression,

but we have made splice-bars with a depression of about one inch in length and about one-eighth inch in depth which were successful in use.

5. The clearance thus provided will prevent damage to the metal at the top of the splice-bar, thus preserving the proper finished condition of the surface of the metal in the depression. The form and full strength of 10 the bars is maintained at the center where they are subjected to the greatest strains, and where, if the condition of the metal is impaired, the danger of fracture is much increased.
15. We do not propose to limit the application of our invention to splice-bars of any particular shape, for it would be a desirable improvement in all forms with which we are acquainted. For instance we have shown 20 in Fig. 5 our invention applied to the so-called "fish plate" of usual shape having the depression 6 both on its upper and lower surfaces to permit reversal.

We claim,

25. 1. A splice-bar for rail joints formed with a central depression on its upper edge to avoid contact with the rail ends.
2. A splice-bar for rail joints having the central portion of its upper edge slightly de-

pressed and correspondingly thickened, to 30 prevent contact with the ends of the rails, while preserving the full strength of the bar at the center.

3. A splice-bar for rail joints formed to fit snugly in the "fishing angle" of the rail, 35 and having a depression in its upper portion adapted to be arranged adjacent the rail ends to insure clearance between the bar and the corners on the under surface of the rail ends.

4. As a new article of manufacture, a 40 splice-bar for rail-joints formed with an upper surface to engage the under side of the rail heads, and having a small depression formed in said upper surface and adapted to underlie the corners on the underside of 45 the rail ends, substantially as shown.

5. The combination in a rail joint of the two rails having their ends arranged adjacent and a splice-bar bolted to said two ends to connect the two rails, said joint being 50 formed to provide a clearance between the upper surface of the splice-bar and the under side of the rail heads adjacent their ends, substantially as described and shown.

In testimony whereof we have signed our 55 names to this specification.

ANDREW J. NEAFIE.
CHARLES B. FRENCH.
